PACKAGE FOR FIREWORKS DEVICES

Application filed May 11, 1928. Serial No. 276,876.

This invention relates to means for packing firework devices, and especially firework devices of the detonating type, and also to cartons, and particularly to cartons for containing fireworks of the detonating type, such, for example, as torpedoes.

It has been common to pack detonating fireworks of this character for shipment loosely disposed in sawdust within paper boxes. Owing to the handling incidental to shipping such detonating fireworks, and especially torpedoes, often shift about and accumulate in one portion of the box, with the result that should the box be suddenly struck or jarred, the torpedoes are sometimes caused to explode, with risk of fire or damage to surrounding objects or even possible injury to persons. Since there is nothing to positively hold the torpedoes away from the outer walls of the box, they very often rest against such walls, thereby increasing the above mentioned hazard. Furthermore, torpedoes and similar detonating fireworks packed loosely in sawdust prevent an untidy appearance when the box is opened by the consumer and it is sometimes difficult and troublesome for the user to find and remove the torpedoes from the sawdust content.

One feature of the invention is to provide a carton of the folding type within which the torpedoes are positively retained in spaced relation with respect to one another and the sides of the carton.

Another feature of the invention lies in the provision of a carton of the above character within which the torpedoes are distributed and spaced through the carton interior and so retained in fixed positions.

A third feature of the invention is to provide a carton of the above character into which torpedoes may be quickly and easily packed and as readily unpacked.

Still another feature of the invention lies in the provision of a carton of the above character that is of simple, strong, construction and of pleasing appearance, both on the outside and as to the arrangement of torpedoes within its interior; the interior spaced arrangement thereof being especially advantageous in facilitating quick location thereof

by the user's fingers when removing the same from the carton.

Other features and advantages will become apparent from the specification, taken in connection with the accompanying drawings 55 wherein the invention is embodied in concrete form.

In the drawings:

Figure 1 is a perspective view showing the carton of this invention with its top and bottom open and ready to receive the torpedo rack, which is shown in the lower portion of the figure;

Figure 2 is a view of a fragment of the torpedo rack;

Figure 3 is a view in elevation with parts broken away of the carton filled with torpedoes, the torpedo rack acting to divide the carton into two chambers, one of which chamber is in the process of being filled with protective sawdust;

Figure 4 is a plan view of the structure shown in Figure 3;

Figure 5 is a view similar to Figure 3, but illustrates one of the chambers completely 75 filled with sawdust, and the carton reversed to dispose the other chamber ready to be filled with sawdust.

Figure 6 is a fragmentary sectional view, with parts broken away, of the torpedoes 80 packed in a different manner from that illustrated in the preceding figures.

Figure 7 is a plan view of the structure shown in Figure 6.

As illustrated in Figures 1 to 5 of the drawings, the carton 1 is adapted to enclose the torpedoes 2 that are carried by the torpedo rack 3. The top of the carton 1 comprises two overlapping inner flaps 4 and 5 and two overlapping and interlocking outer flaps 6 90 and 7. The bottom of the carton 1 likewise comprises two overlapping inner flaps 8 and 10 and two overlapping and interlocking outer flaps 11 and 12.

The torpedo rack 3 comprises a flat rectangular body 13 having turned up flanges 14 and 15 at two of its sides and turned down flanges 16 and 17 at its other two sides. These flanges 14 to 17 have equal heights and are perpendicular to the body 13. The height of 100

the torpedo rack 3 is equal to the combined heights of one of its turned up flanges and one of its turned down flanges, and substantially equal to the interior vertical dimension 5 of the carton when closed. The outer dimensions of the torpedo rack 3 are equal to the inner horizontal dimensions of the carton 1 so that the torpedo rack 3 will fit within the carton 1. The body 13 has a plurality of circular apertures 18 that are adapted to snugly receive the cylindrical torpedoes 2. Radial slits 20 may be provided if desired, in the body 13 adjacent the apertures 18, as illustrated in Figure 2, to enable easier insertion of the torpedoes 2 into their apertures and removal of the same therefrom. When the torpedoes 2 are inserted within the apertures 18, the friction between the cylindrical surfaces of the torpedoes 2 and the margins of the apertures 18 is sufficient to retain the torpedoes within the rack 3.

In preparing the torpedoes for shipment, the torpedo rack 3 carrying the torpedoes 2 is inserted into the carton 1. The top of the carton 1 is closed by folding over inner flaps 4 and 5 and outer flaps 6 and 7, and then the carton is turned upside down into the position illustrated in Figure 3. It will be noted that torpedo rack 3 serves to divide the interior of the carton 1 into two chambers 21 and 22. Chamber 22 is now filled with sawdust 23 which surrounds the portions of torpedoes 2 that extend into chamber 22, and then the inner flaps 8 and 10 are folded over. Flaps 11 and 12 are also folded over and interlocked, thereby closing the bottom of the carton 1. The carton is then turned over, thereby bringing its top into its normal upward position. The flaps 4 to 7 are turned back, opening the top of the carton 1 as illustrated in Figure 5. The chamber 21 is now filled with sawdust around the upwardly projecting torpedo ends, whereupon the carton is finally closed by folding over flaps 4 to 7 and interlocking the flaps 6 and 7. The carton is now closed and ready for shipment. From the above description it will be obvious that a novel method of packing is involved in this invention which generally facilitates the preparation of the articles for shipment and handling.

It will be noted that as thus packed, the torpedoes can not shift or come into contact with one another, nor with the walls of the carton, thereby reducing to a minimum the possibility of accidental explosion as the result of rough handling of the carton either during shipment, commercial handling, or in the hands of the user.

Since the torpedoes are frictionally held 60 against longitudinal movement within the apertures in the rack 3, and as the torpedoes do not extend the entire distance between the top and the bottom of the carton, they are completely surrounded with sawdust which 65 serves to cushion any jolt or jar applied to

the carton. Even should there be insufficient sawdust to completely surround all of the torpedoes, the torpedoes not surrounded by sawdust will nevertheless have an air space between them and all walls of the carton. 70 The sawdust may even be omitted if desired, in which event the spacing of the torpedoes from the walls of the carton and the rigidity of the carton itself and of the torpedo rack will be depended upon to protect the torpedoes from outside forces. 75

As assembled in the torpedo rack the spaced torpedoes present a neat and attractive appearance when the carton is opened by the user and are not all bunched together 80 in a corner of the carton as is sometimes the case where the carton of the invention is not employed, and, furthermore, being symmetrically arranged and retained, removal of the same by the user is greatly facilitated, especially when it is desired not to employ out the saw-dust packing. 85

In Figures 6 and 7, the body 28 of the torpedo rack 24 is provided with a plurality of rectangular apertures 25 for receiving the torpedoes 2. Lugs 26 are formed on the body 28 and project into the recessed ends of the torpedoes 2 when the torpedoes are assembled in the apertures 25. The lugs 26 serve to augment the frictioned force existing between the torpedoes and body 28 in retaining the torpedoes 2 within the apertures 25. 95

It will be noted that the carton of the invention is of exceedingly simple yet strong construction. The body of the torpedo rack, 100 greatly enhances the lateral strength of the carton, since this body extends midway between the top and the bottom of the carton. Likewise the flanges 14 to 17 stiffen the carton vertically. 105

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. 110

What is claimed is:—

1. In a carton for carrying vertically disposed fireworks said carton having inner and outer overlapping flaps at its top and bottom, a rack conforming to the carton interior, said rack comprising, a body provided with apertures for frictionally receiving and supporting the vertically disposed fireworks, flanges formed on said body, one of said flanges resting upon an inner flap at the top of the carton and another of said flanges resting upon an inner flap at the bottom of the carton, the outer flaps of the carton being interlocked to retain the carton in a closed condition. 120
2. In a carton for fireworks having inner and outer overlapping flaps at its top and 125
- 65
- 130

bottom, a rack conforming to the carton interior, said rack comprising, a flat apertured body, the apertures in said body being adapted to frictionally hold fireworks in fixed position in spaced relation from the inner walls of the carton, a pair of upwardly extending flanges provided on opposite edges of said body, said upwardly extending flanges being arranged to abut the inner flaps at the top of the carton, and a pair of downwardly extending flanges provided on other opposite edges of said body, said downwardly extending flanges being arranged to abut the inner flaps at the bottom of the carton, the outer flaps at the top and bottom of the carton being interlocked for the purpose of retaining the carton in closed condition.

In testimony, that I claim the invention set forth above I have hereunto set my hand
20 this 7th day of May, 1928.
